UNITED STATES PATENT OFFICE

2,265,300

HEAT TRANSFER UNIT AND SYSTEM

Carl E. Meyerhoefer, Brooklyn, N. Y., assignor to
 E. A. Laboratories, Inc., Brooklyn, N. Y., a corporation of New York

Application April 2, 1938, Serial No. 199,574

3 Claims. (Cl. 62—126)

This invention relates to a structurally and functionally improved heat transfer unit and system and while the same is capable of use in numerous different associations, it is primarily intended to be employed for the conditioning of air within an enclosure such as the body of a motor vehicle.

Whether employed in this or functionally equivalent installations, it is intended to furnish a unit and set-up of apparatus which may either raise or lower the dry bulb temperature of an enclosure and which system will be of such a simple nature that it may be installed by a mechanic of ordinary skill and will operate without virtually any attention or skilled supervision.

It is an object of the invention to provide a structure such that a maximum heat transfer will be accomplished, the system operating for example with heated water, secured from the cooling system of an internal combustion motor—when it is desired to raise the dry bulb temperature—and functioning with one of any number of desirable refrigerants when it is intended to reduce the dry bulb temperature.

A further object of the invention is that of furnishing a structure of this nature and in which the refrigerant will, at all times, be properly maintained so that the system will operate with maximum efficiency.

A still further object is that of providing a set-up of apparatus which will be of an extremely simple and compact nature, readily capable of being associated with and accommodated within an automobile, the parts being individually simple and rugged in construction, and capable of assemblage by unskilled labor to furnish a unitary and economical system of this type.

According to certain further aspects, the present invention contemplates an improved or alternative structure to that described and shown in my previous application for patent which resulted in United States Patent No. 2,118,263, on May 24, 1938, and identified under the title of "Heat transfer apparatus."

With these and other objects in mind, reference is had to the attached sheets of drawings illustrating practical embodiments of the invention and in which:

Fig. 1 is a view showing diagrammatically the motor of a vehicle and illustrating the system in association therewith;

Fig. 2 is a front elevation of the heat transfer unit and the connections extending therefrom;

Fig. 3 is a transverse sectional view taken along the lines 3—3 and in the direction of the arrows of Fig. 2;

Fig. 4 is a sectional plan view taken along the lines 4—4 and in the direction of the arrows of Fig. 2;

Fig. 5 is an enlarged sectional side view taken

along the lines 5—5 and in the direction of the arrows of Fig. 3;

Fig. 6 is a view similar to Fig. 5, but showing an alternative form of construction;

Fig. 7 is a cross section through the heat transfer unit shown in Fig. 5 taken along the line 7—7 in that view and in the direction of the arrows, and

Fig. 8 is a section taken through the heat transfer unit shown in Fig. 6 along the line 8—8 of that section and again in the direction of the arrows.

The subject matter of the system particularly shown in Figs. 1 to 4 inclusive and as hereinafter described, has been included in divisional application for United States Letters Patent 231,348 for "Cooling system" filed September 23, 1938.

Before continuing with a consideration of the structure heretofore briefly described, it is to be understood that while in many respects the present invention is primarily intended for association with a motor vehicle, it might be employed in numerous other instances and wherever it is necessary or desired to effect heat exchange, and particularly the lowering of air temperatures. Thus, the present drawings and description are to be construed in an illustrative, and not in a limiting sense, except where otherwise indicated in the appended claims.

Thus, referring primarily to Fig. 1, the numeral 10 indicates a motor provided with the usual cooling system from which tubes 11 and 12 extend to the radiator 13. To the rear of the motor there is provided the conventional partition or dash 14 upon which is mounted a heat transfer unit generally indicated at 15, including air passages through which air is forced in heat exchange contact by means of a suitable motor driven impelling member 16. In the present application there has not been shown the conventional and well known connection between the unit 15 and the cooling system of the motor vehicle. One of several well known and accepted manners of achieving this result may be resorted to, it being noted that the present illustration has been confined to the cooling of air rather than the raising of the temperature thereof.

The unit 15 may include any desired construction although it preferably embraces the structures shown in Figs. 5 and 6. In the first of these, the numeral 17 indicates a core presenting a plurality of transverse fluid conducting passages 18 communicating at one end with an upwardly tapered head 19 and at their opposite ends with an upwardly flared head 20. These passages are formed by the presence within the core of spaced horizontally disposed box-like structures defined as will be seen in Fig. 7 with top and bottom walls 50 and 56, side walls 52 and 54, and end walls, one of which appears at 51 in this view, while

the other appears at 57 in Fig. 5. In addition, and as is shown in Fig. 5, the box-like structures are formed along their entire length with angularly disposed sections 65 extending upwardly and equally spaced corresponding sections 66 extending downwardly, complementary portions of adjacent structures being disposed in parallel with the result that the paths 18 extending horizontally through the heat exchange unit are tortuous in character. It will be noted that the structures defining these paths may be secured to the outer sides of the heat exchange unit 53 and 55 by soldering or otherwise securing the side edges 52 and 54 thereto. Also, it is to be observed that the side plates 52 and 54 might be so designed as to seal only the side edges of the passage-ways 18 in the heat transfer unit, thus permitting passageways for liquid or air to extend between the plates 50 and 56, provided opening is made for that purpose in the side plates 51 and 54. Located in the lower portion of the first head is an intake passage 21 while an outlet passage 22 is disposed in the upper end of head 20. A core assembly of this character is preferably disposed with passages separated horizontally and in different heads although this need not necessarily be the case, and if desired a unit such as shown in Fig. 6 may be employed. The latter unit also includes passages 23 communicating at one of their ends with a head 24 and at their opposite ends with a head 25. The latter head is formed with a central partition 26 and in its lower end has an inlet tube 27, while at its upper end an outlet or discharge opening 28 is present. As before observed in connection with Figs. 5 and 7, the heat transfer unit shown in Figs. 6 and 8 may be assembled by spacing horizontally extending box-like structures for top walls 61 and bottom walls 58, and end walls 59 and 60, the latter showing only in Fig. 6. Side walls 61 and 64 are also provided for these box-like structures which are spaced horizontally one above the other to provide a plurality of passageways 23. In addition, each of the horizontally disposed box-like structures is formed with parallel sides of angularly disposed sections reaching maximum points as is shown in 67 and 68. The adjacent surfaces of said structures are complementary in character so that a tortuous path or passageway 23 is provided in each instance. The side walls of said structures may be secured to the sides of the heat transfer unit at 70 and 71. As has heretofore been pointed out in connection with Figs. 5 and 7, both the side walls 70 and 71 as well as side walls 61 and 64 may be omitted for a substantial portion of their length to provide transverse passages for other fluid or air, while at the same time, keeping such transverse passageways separate and distinct from the main chamber of said heat transfer unit. The functioning of both of these core assemblies will hereinafter be more particularly considered. Suffice it to say that if they are being employed for the purpose of cooling, a liquid level substantially equivalent to that indicated in the dotted lines in these figures should be maintained.

Now again referring to Fig. 1, it will be seen that an outlet tube 29 is coupled to the upper end of the unit and an inlet tube 30 is coupled to the lower end of the same. Extending between these tubes is a body 31, the interior construction of which is probably best shown in Fig. 3. In this view it will be noted that a float 32 is positioned within the body and when the liquid level within the core assemblies is at proper height this float, 75

by means of a link 33, serves to maintain valve 34 in closed position against its seat. This seat 35 is disposed below the plane of tube 30 which may form a part of, or be directly coupled to body 31. In case a core such as that shown in Fig. 6 is employed, tubes 29 and 30—or the continuation thereof—will, of course, extend substantially in line with the body 31. If, on the other hand, the inlet and outlet openings of the core assembly are disposed in opposite corners of the same and as has been shown in Fig. 5 a tube 36 will connect with the lower end of body 31 and couple the same to tube 30.

Extending from the upper end of body 31 is a tube or pipe 37 which is coupled to a suitable pump 38 driven by the fan belt 39 of the motor, or by any other suitable power source. The outlet of the pump is connected to a condenser 40 which in turn discharges into a tank 41, the latter conducting the distillate through a tube 42 coupled to the lower end of body 31.

The condenser-tank assembly may be provided with a filler plug 43 through which the system may be charged with a refrigerant to the proper level. It will also be noted that there extends from this assembly an air pipe 44 which connects with the return or inlet tube 30. This connection is preferably effected as shown in Fig. 4, by employing a packing assembly 45 through which the pipe 44 passes into the inlet tube of the core assembly and adjacent the lower end of the same. At this point it is preferred that the pipe terminate in an end portion having the characteristics of a nozzle 46, as shown especially in Figs. 5 and 6, so that not alone is the air or vapor directed as desired, but also an expansion-valve effect is achieved.

In operation the system is charged in any desired manner as afore indicated and the plug 43 seals the tank. The refrigerant may be one of a number of commercially available substances. In certain respects, however, it is preferred to employ methylene chloride, commonly known as "Carene," in that a material of this type is non-caustic, non-corrosive, and fireproof, and also has the advantage that it is not injurious to human beings even if a leak should develop and the vapors should be inhaled.

With the pump 38 in operation a vacuum of, for example, 15 to 20 inches will occur within tube 37. If methylene chloride is employed, it will be found that at atmospheric pressure it boils at a temperature of substantially 104° F. With 10 inches of vacuum it boils at a temperature of 85° F. If, however, air is permitted to flow through the body of liquid, it will be found that the boiling effect continues until a temperature of 58° F. is reached. Of course, when the vacuum is increased above 10 inches, this effect continues at much lower temperatures. Conversely, the refrigerant will condense at a temperature of substantially 104° F. at atmospheric pressure. However, under 5 lbs. pressure, it will condense at a temperature of 125° F. while if the pressure is stepped up to 10 lbs. above atmospheric, the methylene chloride will condense at a temperature of 135° F.

Thus, with a vacuum exerted by pump 38 through tube 37 the temperature of the fluid within unit 50 will reduce rapidly in that it will quickly absorb heat, this being especially true with air passed through the body of liquid as afore brought out. Consequently vapor surcharged with refrigerant flows through tube 37 towards the pump 38. Necessarily, a certain

amount of the refrigerant liquid will be entrained within this vapor and it would be extremely objectionable if these liquid particles were drawn into the pump. This is prevented, however, incident to the body 31 which in certain respects acts as a trap. In this connection tube 29 or its continuation opens into the body 31 at a lower level than the entrance of tube 37 and at an angle to the axis of the latter tube. Consequently entrained particles of moisture will fall 5 downwardly into the body 31 and serve to maintain the float 32 in raised position. Thus valve 34 will remain closed. If, however, the level within this body drops below that which is proper, valve 34 will open and additional refrigerant will be free to flow from the condenser-tank assembly through tube 47 into body 31 under the influence of the pressure existing within the condenser-tank assembly, it being understood that this pressure has assisted and accelerated the 10 condensing of the refrigerant.

In this manner the level will at all times be properly maintained. Vapor will be discharged through pipe 44 and incident to the pressure which this vapor is under the air will probably 15 be surcharged with refrigerant. Incident to the expansion valve effect achieved by the nozzle 46 or otherwise, the air will, of course, expand upon entering the unit 15 and will be free to absorb additional vapor, thus accordingly lowering the temperature of the refrigerant within the unit.

Considering the construction of unit present in Fig. 5, it will be observed that the air or vapor discharged through nozzle 46 will rapidly rise 20 through the refrigerant within head 19 and will flow through the upper courses of passages 18 to head 20. In so doing it will, of course cause a cooling of the refrigerant and the latter, incident to the resultant thermo-dynamic cycle, will rotate or circulate in a clockwise direction as indicated by the arrows. The vapors will be drawn through outlet 22 and distributed as afore described, and the fan or impeller 16 will be passing air through the spaces in intervening passages 25 18.

In the case of a structure shown in Fig. 6 the air will again be discharged from the nozzle 46, will flow upwardly within head 25 and in advance of the partition 26 will flow through passages 23 30 to head 24. Through the latter it will rise until it may pass above the refrigerant, back to head 25, and so through the outlet 28. In this latter form of construction the refrigerant situated generally below partition 26 will circulate in a 35 counter-clockwise direction, while that above the partition will circulate in a clockwise direction.

Thus, in both forms of unit the air will evenly cause a cooling of all parts of the liquid body in that during a given interval of time a complete 40 cycle of fluid circulation will occur. Also, in both forms of the apparatus it will be appreciated that adjacent substantially the highest liquid level the flow of air through the passage will enhance to a large extent the refrigerating effect.

It will, of course, be understood that the liquid level need not necessarily be maintained as indicated in Figs. 5 and 6. In fact, in certain instances where it is desired to reduce noise, the liquid level may be sufficiently high to permit of a certain quantity of the liquid flowing through the outlet pipe. In that event, it will be apparent

that the liquid will simply flow to the float chamber and be returned through the inlet pipe and the operation of the system will not be interfered with.

Thus, among others, the several objects of the invention as afore noted are achieved. Obviously, numerous changes in construction, and rearrangement of the parts, might be resorted to, without departing from the spirit of the invention as defined by the claims.

Having described my invention, what I claim as new and desire to secure by Letters Patent is:

1. A heat transfer unit to receive a body of liquid and through which bubbles of gas are to flow upwardly, said unit including a core presenting substantially horizontally extending tortuous passages, vertically extending head members disposed adjacent each end of said core and having communication with said passages, said unit being formed with an inlet opening adjacent the lower end of one of said head members and an outlet opening formed adjacent the upper end of one of said head members, means for maintaining the height of the body of liquid within said unit below the plane of said outlet opening, and the head member of which said inlet opening forms a part being tapered upwardly whereby to induce a flow of bubbles through said head member toward said passages and below the upper level of the liquid body before said bubbles may escape to said outlet opening.

2. A heat transfer unit to receive a body of liquid and through which bubbles of gas are to flow upwardly, said unit including a core presenting substantially horizontally extending tortuous passages, vertically extending head members disposed adjacent each end of said core and having communication with said passages, said unit being formed with an inlet opening adjacent the lower end of one of said head members and an outlet opening formed adjacent the upper end of one of said head members, means for maintaining the height of the body of liquid within said unit below the plane of said outlet opening, the head member within which said inlet opening is formed being tapered in an upward direction and toward said passages, the outlet opening being formed in the opposite head member and adjacent the upper end of the same, said latter member being flared upwardly whereby the bubbles may flow upwardly through the first named head member and will be diverted through said passages below the upper level of said liquid body and may thence flow through said outlet opening.

3. A heat transfer unit including a core comprising substantially horizontally extending passageways, each passageway embracing equally spaced sections angularly disposed to the horizontal, and alternating upwardly and downwardly with respect thereto, such sections providing a tortuous path in said passageways, head members connected to the ends of said passageways and disposed in generally vertical planes, pipes connected to said unit and for causing a flow of fluid through the same, and circulation causing means in a head member, said head members being formed to cooperate with said circulation causing means to induce a circulation of liquid throughout said passageways and head members as said fluid flows through said unit.

CARL E. MEYERHOEFER.
